UNITED STATES PATENT OFFICE.

JAMES W. ALEXANDER, OF PITTSBURGH, PENNSYLVANIA, ASSIGNOR TO AMERICAN AUTO LOCK COMPANY, OF PITTSBURGH, PENNSYLVANIA, A CORPORATION.

HOOD-LOCK.

1,265,026.

Specification of Letters Patent.

Patented May 7, 1918.

Application filed June 14, 1917. Serial No. 174,767.

To all whom it may concern:

Be it known that I, JAMES W. ALEXANDER, a citizen of the United States, residing at Pittsburgh, in the county of Allegheny and

5 State of Pennsylvania, have invented certain new and useful Improvements in Hood- Locks, of which the following is a specification.

My invention relates to locking devices 10 and more particularly to hood locks for automobiles and has for one of its objects the provisions of a device that is electrically controlled.

Other objects are to prevent sticking of 15 the parts, to provide a lock that will be out of sight, and to generally improve the art by the production of a device that will be cheap to manufacture, durable, and efficient.

A preferred form of my invention is illustrated in the accompanying drawings but it will be understood that changes in construction within the scope of the appended claims may be made without departing from the spirit of my invention.

25 Figure 1 is a front plan view of my lock, Fig. 2 is a longitudinal sectional view on the line II, II, of Fig. 1,

Fig. 3 is a cross sectional view on the line III, III, of Fig. 2,

30 Fig. 4 is a bottom plan view partly broken away to show the construction of the latch,

Fig. 5 is an end view showing the finger engaging portion of the latch,

Fig. 6 is a perspective detailed view of 35 the latch, and

Fig. 7 is a diagrammatic view of the circuit in which the device is used.

Referring more particularly to the drawings, the letter A designates the casing of 40 my lock adapted to be secured in the channel frame of an automobile, and comprising a top 2 having elongated aperture 2^a therein, a side 3, a short side 4, a lug 4' and an end 5 having an elongated slot 6 therein. A 45 three sided inner casing 7 is secured in the casing A and carries an electromagnet 8 and contact posts 9 and 10 in circuit with the electromagnet and adapted to receive lead wires to a suitable source of current.

50 An armature latch, having a body portion 12 of suitable material subject to magnetism and catch portion 13 and finger release 14 of non-magnetic material, is pivoted in the casing A by pivot arms 15 and 15^a which 55 are inserted in suitable apertures in the top

2 and lug 4'. The finger release 14 extends through the elongated slot 6 in the end 5 of the casing.

The body portion 12 of the armature latch is provided with a suitable lug 12' on a line 60 with the lug 11 and a coil spring 23 is mounted on the lugs 11 and 12' in such a manner as to normally hold the armature latch out of engagement with the electromagnet 8.

A suitable keeper 16 adapted to be secured to the hood of an automobile and having an aperture 16^a is adapted to pass through the slot 2^a in the top 2 and be engaged by the catch 13 of the armature.

Referring now to Fig. 7 of the drawings, B designates the main switch of an automobile having a post 17 connected by suitable wire to the battery 18, a second post 19 having lead wire 20 terminating in switches 75 21 and 21^a and a contact lever 19^a is adapted to close the circuit between the posts 17 and 19.

The switches 21 and 21^a are connected to the one pole of the electromagnet 8. A suitable lead wire 22 is connected to the other pole of the magnet and to the battery 18. The contact lever 19^a being closed the circuit is then complete but for switches 21 and 21^a. If either or both switches 21 or 21^a are 85 closed the circuit will then be complete through the magnets 8 in the hood locks and wire 22 to the battery, energizing the magnet 8 and attracting the body portion 12 of the armature latch and releasing the keeper 16. 90

Having thus described my invention, what I claim is:

1. A device of the class described comprising a main casing, a supplemental casing secured within said main casing and cut 95 away at one end to form a projecting lug, an armature pivoted to said first named casing, a catch of non-magnetic material secured to said armature, a lug formed on said armature in line with the lug on said supplemental casing, an electromagnet secured within said supplemental casing and adapted to attract said armature when energized, and a coil spring mounted on said lugs for normally holding said armature out of engagement with said electromagnet.

2. In combination with an automobile having a hood, a lock comprising a main casing, a supplemental casing cut away at one end to form a projecting lug, an arma-

ture pivoted to said first named casing, catch and finger engaging members of non-magnetic material secured to said armature, said finger engaging member being adapted to 5 pass through an aperture in said casing, a lug formed on said armature in a line with said lug on said supplemental casing, an electro-magnet secured within said supplemental casing and adapted to attract said

armature when energized, a coil spring 10 mounted on said lugs for normally holding said armature out of engagement with said electromagnet and a keeper secured to said hood and adapted to be engaged by said catch. 15

In testimony whereof I hereunto affix my signature.

JAMES W. ALEXANDER.
